CONTAINER FOR LIQUID-DISPENSING PLIABLE BAG

Leslie Barr, Glenview, and Efrem M. Ostrowsky, Highland Park, Ill., assignors to Nibot Corporation, Chicago, Ill., a corporation of Illinois

Filed Oct. 20, 1965, Ser. No. 87,610

Term of patent 14 years

(Cl. D58—12.6)

F1 — 1

F1 — 3

FIGURE 1 is a perspective view, taken from the front and slightly to one side, of a container for liquid-dispensing pliable bag embodying our new design;

FIG. 2 is a front elevational view thereof on an enlarged scale;

FIG. 3 is a rear elevational view thereof;

FIG. 4 is a top plan view thereof; and

FIG. 5 is a bottom plan view thereof.

We claim:

The ornamental design for a container for liquid-dispensing pliable bag, substantially as shown.
